UNITED STATES PATENT OFFICE.

JOHN C. MILLER, OF WATERBURY, CONNECTICUT, ASSIGNOR TO THE MATTHEWS & WILLARD MANUFACTURING COMPANY, OF SAME PLACE.

DESIGN FOR A SLAB FOR TABLE-TOPS.

SPECIFICATION forming part of Design No. 23,285, dated May 22, 1894.

Application filed April 23, 1894. Serial No. 508,719. Term of patent 3½ years.

To all whom it may concern:

Be it known that I, JOHN C. MILLER, of Waterbury, in the county of New Haven and State of Connecticut, have invented a new Design 5 for Slabs for Table-Tops, (Case A;) and I do hereby declare the following, when taken in connection with the accompanying drawing and the letters of reference marked thereon, to be a full, clear, and exact description of the 10 same, and which said drawing constitutes part of this specification and represents a top or face view of a slab for table-tops illustrating the design.

This invention relates to a design for a slab 15 for table-tops, and the design consists in the configuration as shown in the accompanying illustration.

The central portion of the top is oblong, surrounded by a border A. At the center of each 20 side of the border is a cherub B, its outspread wings merging into scroll tips, connected at the head and upper parts of the wings to the inner plain band C. The neck merges into a leaf ornamentation D. Branching from each 25 side of, and overlying the neck, is a foliated

scroll E, which passes under the wings, and overlaps a perforated and beaded segment-shaped ornament F. At the ends are two upwardly curved scrolls G, springing from a trefoil ornament H, surmounting a slightly 30 convexed plain ornament J, and separated from the plain inner band C by a narrow fret-work I. At each corner is a nearly circular, slightly convexed plain ornament K, its outline broken by overlapping narrow 35 scrolls, and having springing from it floriated branches and ornate scrolls and conventionalized leaves, connecting the corners with the sides and ends, all as shown in the accompanying illustration. 40

I claim—

The design for a slab for table-tops as herein shown and described.

In testimony whereof I have signed this specification in the presence of two subscribing 45 witnesses.

JOHN C. MILLER.
